UNITED STATES PATENT OFFICE

165,620

CENTRIFUGE SPIDER

George B. Via, Red Bank, N. J., assignor to The Gerin Corporation, Red Bank, N. J., a corporation of New Jersey

Application November 22, 1949, Serial No. 6,185

Term of patent 14 years

(Cl. D16—2)

To all whom it may concern:

Be it known that I, George B. Via, a citizen of the United States, residing in Red Bank, in the county of Monmouth and State of New Jersey, have invented a new, original, and ornamental Design for a Centrifuge Spider, of which the following is a specification, reference being had to the accompanying drawing, forming part thereof.

Fig. 1 is a top plan view of a centrifuge spider embodying my new design, whereby alternate tube shields are held at one level and the remaining alternate shields are at another level; the bottom plan view of the same being essentially like the illustrated top plan view in its salient details;

Fig. 2 is a side elevational view of the centrifuge spider shown in Fig. 1.

I claim:

The ornamental design for a centrifuge spider, substantially as shown.

GEORGE B. VIA.
